(57) **CLAIM**

The ornamental design for the gas fireplace front, as shown and described.

DESCRIPTION

FIG. 1 is a perspective view of the gas fireplace front; and, FIG. 2 is a top plan view thereof, the bottom being a mirror image of that shown.

The surface(s) or portion(s) of the article not shown in the drawing or described in the specification form(s) no part of the claimed design.

The broken-line showing of environmental structure in FIGS. 1 and 2 is for illustrative purposes only and forms no part of the claimed design.
